UNITED STATES PATENT OFFICE.

FREDERICK H. WIARD, OF EAST AVON, NEW YORK.

WASHING-MACHINE.

SPECIFICATION forming part of Letters Patent No. 653,429, dated July 10, 1900.

Application filed October 10, 1898. Serial No. 693,098. (No model.)

To all whom it may concern:

Be it known that I, FREDERICK H. WIARD, a citizen of the United States, residing at East Avon, in the county of Livingston and State 5 of New York, have invented new and useful Improvements in Washing-Machines, of which the following is a specification.

This invention relates more particularly to that class of washing-machines which comprise an oscillating tub or vessel provided in its bottom with a roughened surface or rubber, an upper oscillating rubber arranged in the tub and coöperating with the rubber of the tub, an upright hand-lever for oscillating the 15 rubbers in opposite directions, and a yoke or cross-bar carrying the upper rubber and pivoted to a standard at one side of the tub and having its free end detachably secured to a bracket or support at the opposite side of the 20 tub, so that upon releasing the detachable end of the yoke the same can be raised or swung out of the way for placing the clothes in the tub and removing them.

One of the objects of my invention is to 25 provide improved means for pivoting the yoke to the frame in such manner that the yoke and the upper rubber carried thereby can be readily removed from the machine, so that the latter can be more conveniently carried from place to place.

In the accompanying drawings, consisting 35 of two sheets, Figure 1 is a sectional elevation of my improved washing-machine, showing the parts in position for use. Fig. 2 is a top plan view thereof. Fig. 3 is a fragmentary sectional elevation of the machine, showing the yoke unlocked and retracted to clear the wash-wringer preparatory to raising the yoke. Fig. 4 is an enlarged side elevation of 40 the pivotal connection between the yoke and its support. Fig. 5 is an enlarged longitudinal section of the free end of the yoke and its supporting-bracket, showing the fastening for securing the yoke to the bracket. Fig. 6 is a transverse vertical section in line 45 66, Fig. 5.

Like letters of reference refer to like parts in the several figures.

The stationary supporting-frame of the 50 machine is composed of uprights A A', having feet A² and upper and lower cross-pieces or boards A³ A⁴, connecting the uprights, the

upper cross-piece extending laterally beyond the short upright A and the other upright A' extending some distance above said upper 55 cross-piece.

B is the tub or vessel for the clothes, which is supported upon a rotary or oscillating platform C, mounted on the upper end of an upright shaft D. The tub is preferably remov- 60 ably secured to this platform by radial pins e, arranged on diametrically-opposite sides of the tub and engaging with bifurcated lugs e', secured to the projecting arms of the platform, as shown in the drawings, or by any 65 other suitable means. The upright shaft D is preferably supported at its lower end in a ball-bearing of any suitable construction mounted on the lower cross-piece A⁴ and turns near its upper end in a suitable ball or 70 roller bearing mounted on the upper cross-piece A³ to reduce the friction to a minimum.

E designates the raised ribs or bars secured to the inner side of the tub-bottom and forming, with said bottom, the lower rubber of the 75 machine.

F is the upper rubber, arranged in the tub in close proximity to the rubber thereof and having ribs on its under side, in a well-known manner. This upper rubber is secured to the 80 lower end of an upright shaft G, which is suspended from the movable yoke or cross-bar H, so that the same is raised and lowered with the yoke. The shaft G is square, as shown in Figs. 1 and 2, and free to slide vertically 85 in a bearing-sleeve g, which is provided with a square bore to fit the shaft and which is journaled in the yoke in the customary manner to allow the shaft to oscillate in the yoke. The upper and lower rubbers are oscillated 90 in opposite directions by any suitable means, the devices shown in the drawings for this purpose consisting of an upright hand-lever I, pivoted between its ends to a standard I', and arms j j', secured to the tub-platform and 95 the oscillating bearing-sleeve g, respectively, and connected with the upper and lower arms of the hand-lever by links j² j³. The standard I' is secured to the overhanging portion of the upper cross-piece A³.

I² is a standard mounted on the cross-piece A³ between the tub B and the lever-standard I' and stiffened by a brace I³.

The yoke is pivotally mounted at one end

on the standard I^2 in such a manner that the yoke is free to slide outwardly on the same as well as swing upwardly and downwardly thereon. For this purpose the standard is provided at its upper end with a pair of elongated bearings or horizontally-slotted lugs k , arranged side by side, and the yoke is provided with depending arms l , having laterally-projecting pivots or studs l' , which engage in the slots of the lugs k , whereby the yoke is hinged to the standard and at the same time free to slide lengthwise thereon. The slotted lugs k are provided in their upper sides with openings k' for disengaging the pivots of the yoke from the lugs when it is desired to remove the yoke from the machine. The free end of the yoke is detachably secured to a bracket m , projecting inwardly from an upright board or support N , which is arranged at the upper end of the upright A' and to which the wash-wringer is clamped, as shown by dotted lines in Figs. 1 and 2. This bracket is preferably constructed in the form of a seat or socket which is open at its top and its inner end, as shown in Figs. 3 and 5, and the free end of the yoke is detachably locked in the bracket by any suitable fastening. The preferred fastening, which is shown in the drawings, consists of an upright pawl or latch o , pivoted by a transverse pin in a longitudinal slot or recess o' , formed in the yoke, and provided at its projecting lower end with a hook or shoulder o^2 , adapted to pass through a longitudinal slot p , formed in the depressed bottom of the bracket m , and to interlock with the inner edge thereof, as shown in Fig. 5. The latch is locked in this position by a horizontally-swinging cam or wedge q , pivoted to the upper side of the yoke and engaging under a nose q' , formed at the projecting upper end of the latch on the inner side thereof. This wedge prevents the lower arm of the latch from swinging outwardly and becoming disengaged from the bracket. Upon moving the wedge aside, so as to clear the nose of the latch, the latter is unlocked, and upon pushing the upper arm of the latch inwardly its hook is disengaged from the bracket m , releasing the free end of the yoke therefrom.

When the free end of the yoke is attached to the the wringer-board N , the wringer overhangs the same, as shown by dotted lines in Fig. 1, and when it is desired to remove the upper rubber from the tub for removing or introducing clothes the yoke is unlocked from the bracket of the wringer-board and slid lengthwise away from said bracket, so that its free end clears the wringer, when the yoke can be swung upwardly without the necessity of removing the wringer from the tub. In order to detach the yoke from the machine, it is only necessary to bring its pivot-pins l' opposite the apertures k' of the slotted lugs k and withdraw the same from the lugs. By this construction the yoke can be quickly detached without the use of a wrench or other

tools. The ready detachability of the yoke is a desirable feature in machines of this kind in carrying the machine about. The same is clumsy and awkward when the yoke remains attached to the machine, and, furthermore, when the yoke is readily detachable the upper rubber, which becomes water-soaked in use, can be removed from the machine and stored in a cool place after completing the washing, thereby preventing warping or checking of the same, which is liable to occur when the rubber is stored in a warm place, and also avoiding the necessity of carrying the whole machine for this purpose.

I claim as my invention—

1. The combination with the oscillating tub and the stationary supporting-frame of the machine having standards arranged on opposite sides of the tub, of a horizontally-slotted lug or bearing arranged at the upper end of one of said standards and provided between its ends with an opening which communicates with the slot of the lug, and a vertically-swinging yoke or cross-bar carrying a rubber and provided at one end with a horizontal pivot which is arranged in said slotted lug and which is adapted to be inserted and removed through the opening thereof, substantially as set forth.

2. The combination with the stationary frame of the machine and an oscillating tub or vessel, of standards or supports arranged on opposite sides of the tub, a bracket or socket arranged on one of said standards and provided in its bottom with a slot or recess, a yoke or cross-bar carrying a rubber and pivoted at one end to one of said standards and having at its opposite end an upright latch pivoted to swing lengthwise of the yoke and provided below the yoke with a hook which interlocks with the opening of said bracket and means for retaining said latch in engagement with said bracket, substantially as set forth.

3. The combination with the stationary frame of the machine and an oscillating tub or vessel, of standards or supports arranged on opposite sides of the tub, a bracket or socket arranged on one of said standards and provided in its bottom with a slot or recess, a yoke or cross-bar carrying a rubber and pivoted at one end to one of said standards and having at its opposite end an upright latch pivoted to swing lengthwise of the yoke and provided above the yoke with a locking-nose and below the same with a hook which interlocks with the slot of said bracket, and a laterally-swinging locking cam or wedge pivoted to the upper side of the yoke and adapted to engage under the nose of the said latch, substantially as set forth.

Witness my hand this 27th day of September, 1898.

FREDERICK H. WIARD.
